Des. 192,849
Patented May 22, 1962

192,849

FLOOR RECEIVER FOR FOLDING DOORS

Alfred P. McEvoy, 5534 Montrose, and Tym F. Seay,
4742 Elsby Ave., both of Dallas, Tex.

Filed Nov. 23, 1956, Ser. No. 43,899

Term of patent 3½ years

(Cl. D10—7)

Fig. 1

Fig. 2

Fig. 3

Fig. 4

Fig. 5

FIGURE 1 is an upper perspective view of a floor receiver for folding doors showing our new design;

FIGURE 2 is an end elevation of the floor receiver;

FIGURE 3 is a top plan view of the floor receiver;

FIGURE 4 is a bottom perspective view of the floor receiver; and,

FIGURE 5 is a side elevation of the floor receiver.

We claim:

The ornamental design for a floor receiver for folding doors, substantially as shown.
